UNITED STATES PATENT OFFICE

MAURICE GOUDARD, OF NEUILLY-SUR-SEINE, FRANCE, ASSIGNOR TO SOCIETE ANONYME SOLEX, OF NEUILLY-SUR-SEINE, FRANCE, A SOCIETY OF FRANCE

CARBURETOR

Application filed November 20, 1929, Serial No. 408,635, and in Belgium December 4, 1928.

The present invention relates to carburetors and, more particularly, to those of the type provided with a pump intended to increase the supply of fuel during rapid acceleration.

In carburetors of the type referred to hereinabove, the pump actuated as a rule by movement of the throttle, is arranged to provide a supplementary fuel feed over and above that being supplied from the carburetor nozzle or nozzles by the aspirating action of the motor.

One of the objects of the invention is to provide a pump-carburetor assembly in which the feed from the fuel nozzles due to the suction exerted thereon is entirely replaced by the feed from the pump during the period of rapid acceleration.

Another object is to provide a pump-carburetor assembly in which the pump and the carburetor nozzles serve alternate automatically as fuel sources in accordance with the rate of movement of the throttle.

A further object is to provide a two part form of carburetor body assembly permitting easy access to, and repair of, the various operating elements.

A still further object is to provide a form of assembly permitting the pump-carburetor assembly to be transformed quickly into an ordinary carburetor without pump.

Another object is to provide a form of assembly permitting easy detachment of the pump.

Still other objects will appear in the course of the detailed description now to be given with reference to the accompanying drawing in which the single figure represents an elevation partially in section of one constructive embodiment of the invention.

Referring to the drawing, there is shown a carburetor body composed of an upper portion 1 formed in one piece and comprising the mixing chamber casing and venturi, the throttle and the cover for the constant level reservoir,—and a lower one-piece portion 2 including a float chamber 3 provided with the usual float operated needle-valve, said float chamber communicating via a passage 4 with a vertical bore 5 feeding auxiliary nozzle

7 and main nozzle 8 of current design. Bore 5 terminates at its upper extremity in a calibrated orifice 6 and at its lower extremity in an assembly composed of a plug 10 threadedly engaging with an extension 9 of casting 2, said plug having a pair of transverse passages 19, 20 and a longitudinal bore 11 therein,—and a bell-shaped element 12 slidably mounted in bore 11 and having a longitudinal bore 13 formed therein terminating in an orifice 14. A casting 15 is supported between the head of plug 10 and casting 9 (proper plastic packing elements being intercalated to prevent leakage) and is provided with a passage 18 communicating at one extremity with orifice 19 or 20 and at its other extremity with the compression side of the pump. The latter is composed of a tube 16 interengaging with casting 15, a piston 21 resiliently supported between opposed springs 22, 23, and a tube 24 fitting telescopically over tube 16. A lever 25, rigidly attached to the throttle, transmits the movements of the latter to the end of tube 24.

The hereinabove described structure functions in the following manner:

When the throttle is nearly closed, spring 22 lifts piston 21 and the elements thereabove upward and tube 16 fills with carburant via passages 18, 19, 13, 14, 5 and 4, bell 12 remaining in lowered position and permitting carburant to feed nozzles 7 and 8 via orifice 6; if now, the throttle is opened slowly, piston 21 will force the liquid therebelow through orifice 14 and the carburetor will function as if the pump were not attached thereto; if, contrariwise, the throttle is opened quickly, the rapid compression of the liquid in tube 16 will be transmitted to bell 12, the latter will move upward into the position shown in dotted lines, its conical end will engage in orifice 6, the flow of carburant via passages 4 and 5 will be cut off, and nozzles 7 and 8 will be fed exclusively from the pump; as soon as the pressure of the liquid in the pump falls to a point where bell 12 is no longer sustained, the latter will descend to the position shown in full lines, and the feed of carburant to nozzles 7 and 8

will be resumed via passage 4, bore 5, and orifice 6.

In order that the above operations occur as described the weight of bell 12 and the effect of spring 23 should be adjusted so that the former rises only when the amplitude and the rate of descent of element 24 are of proper magnitude.

It is to be noted that the entire upper portion 1 of the carburetor body may be detached from the lower portion 2 supporting the pump assembly, by merely unscrewing the bolt or bolts holding castings 1 and 2 together, the line of junction between the latter being chosen so as to give easy access to the float chamber and the nozzles i. e. the line shown in the drawing. It is to be noted further that since lever 25 is not connected to tube 24 but merely rests thereon, the unscrewing of plug 10 permits the entire pump assembly to be detached from the carburetor body. In the event that the pump does not function properly for any reason, plug 10 may be unscrewed (together with bell 12) and replaced by a plug not having orifices of the type 19, 20 therethrough, bell 12 being removed entirely. Communication between the pump and orifice 6 being then cut off, nozzles 7 and 8 will then function alone to supply fuel to the mixing chamber.

What I claim is:—

1. In a carburetor; a mixing chamber, a throttle positioned in said mixing chamber, a nozzle positioned to deliver carburant to said mixing chamber, a reservoir adapted to contain carburant, a first passage communicating at one extremity with said reservoir and, at its other extremity with said nozzle, a pump, a second passage communicating at one extremity with said pump and, at its other extremity with said nozzle, and means actuable by the compressive action of said pump to cut off communication between said nozzle and said first passage.

45 2. A structure as defined in claim 1, in combination with means operative by movement of the throttle to actuate said pump.

3. In a carburetor, a mixing chamber, a nozzle positioned to deliver fuel to said mixing chamber, a fuel reservoir and a fuel pump provided with passages communicating with said nozzle, and means operative to cut off communication between the nozzle and reservoir when the pump is supplying 55 fuel to the nozzle.

4. In a carburetor, a mixing chamber, a nozzle positioned to deliver fuel to said mixing chamber, a throttle controlling the mixing chamber, a fuel reservoir provided with 60 a passage communicating with said nozzle, a compression pump communicating with said nozzle, and means operative to cut off communication between the nozzle and the reservoir when the value of the compression in 65 said pump reaches a predetermined value.

5. A structure as defined in claim 4, in combination with means operative by said throttle to actuate said pump.

6. In a carburetor, a mixing chamber, a throttle controlling said mixing chamber, a nozzle positioned to deliver carburant to said mixing chamber, a reservoir and a compression pump adapted to supply carburant, passages extending from said reservoir and said pump to said nozzle, said passages forming an angle with one another, a valve mounted in the passage leading to the pump and positioned to block the passage leading to the reservoir under the action of the compressed carburant delivered by the pump, and means for transmitting movements of the throttle to the pump.

7. In a carburetor, a mixing chamber, a throttle controlling the mixing chamber, a nozzle positioned to deliver carburant to the mixing chamber, a reservoir and a pump adapted to supply carburant, passages extending from the reservoir and the pump to said nozzle, said passages forming an angle with one another, a valve slidably mounted in the passage leading to the pump and positioned to move across the mouth of the passage leading to the reservoir, said valve being formed so as to offer a limited resistance to the flow of carburant from the pump to the nozzle, and means for transmitting movements of the throttle to the pump.

8. In a pump carburetor assembly, a carburetor assembly unit comprising a float chamber, a mixing chamber, a throttle controlling the mixing chamber, a nozzle, a first passage extending between the nozzle and the float chamber, and a second passage forming an angle with said first passage,—a fuel pump assembly unit comprising a pump and a conduit adapted to be connected to the carburetor assembly,—and means for maintaining said pump and carburetor units in assembled relation comprising a plug traversing said conduit and threadedly engaging in said second passage, said plug carrying valve means operative to cut off communication between the nozzle and said first passage, upon operation of said pump.

In testimony whereof I affix my signature. 115
MAURICE GOUDARD.
